CARRYING CARTON

Lewis P. Weiner, Milwaukee, Wis., assignor to Pabst Brewing Company, Peoria Heights, Ill., a corporation of Delaware

Application June 18, 1952, Serial No. 294,145

5 Claims. (Cl. 229—52)

This invention relates to paperboard cartons of the type designed to hold a relatively small number of cans of canned goods as, for instance, a half dozen cans of beer and has as its purpose to provide a carton of this type equipped with a convenient carrying handle which may be lifted from a retracted inoperative position in which it does not interfere with stacking of cartons upon one another, to an operative position above the top of the carton where it may be comfortably grasped. This invention is, therefore, concerned generally with the type of carton shown in Patents Nos. 1,949,986, issued March 6, 1934, to G. E. Whalley; 2,062,451, issued December 1, 1936, to W. F. Forster, and more particularly with cartons like that of the Harold E. Rue Patent No. 2,284,989, issued June 2, 1942.

In cartons of this type heretofore available, the lifting force was transmitted from the handle to the top wall of the carton generally at small localized areas, and since the top wall of the carton was formed by folding down flaps hinged to the side and end walls, the problem of preventing the cover from being pulled open had to be met. Another disadvantage of carrying cartons of the past is that in order for the handle not to preclude stacking of one carton on the other, it was depressible fully within the carton, and when so depressed was not easily withdrawn and because of its being practically hidden from view often was not found by the user.

With an appreciation of these and other disadvantages of carrying cartons now on the market, this invention has as one of its objects to provide a handle equipped carrying carton especially adapted to the carrying of a few cans of beer, in which the cans stand vertically and the top wall of the carton is one continuous panel connected by continuous side walls to the bottom of the carton so that lifting force applied to the top wall does not tend to pull the carton open.

Another object of this invention is to provide a handle equipped carrying carton especially adapted to the carrying of a few cans of beer, in which the ends of the handle have relatively large areas of contact with the top of the carton so that the lifting force is distributed over a substantial portion of the top wall.

Another object of this invention is to provide a carrying carton of the character described equipped with a handle formed of paperboard but in which the handle is disposed flatwise above the carton top and in plain view so that it cannot be missed and is easily lifted from its inoperative flat position in which it does not interfere with stacking of cartons one on the other, to its carrying position presenting a comfortable hand grip.

Another object of this invention resides in the provision of novel means for reinforcing those regions of the top wall of the carton in which the greatest strain occurs during the carrying of the carton by its handle.

Still another object of this invention is to provide a carton of the character described wherein the handle is entirely separate from the carton blank but may be easily and quickly assembled therewith by automatic machinery,

2

and which upon assembly with the carton blank in nowise interferes with the formation of the carton and the packaging of its contents therein.

In this connection it is another object of this invention to provide a carrying carton of the character described which may be wrapped about its contents by automatic machinery to thus assure tighter packaging.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in

20 which:

Figure 1 is a perspective view of a handy carrying carton constructed in accordance with this invention and illustrating its handle lifted to its operative carrying position, a portion of the carton being broken away to illustrate the disposition of its contents therein;

Figure 2 is a perspective view of the handle per se;

Figure 3 is a top plan view of one end portion of the carton;

Figure 4 is a cross sectional view taken through Figure 3 on the plane of the line 4—4 but illustrating only part of the carton and contents and on an enlarged scale;

Figure 5 is a detail sectional view, on an enlarged scale, through Figure 3 on the plane of the line 5—5 illustrating particularly the manner in which the end portions of the handle coat with the carton contents and the adjacent end walls of the carton to limit the movement of the ends of the handle toward one another;

Figure 6 is an enlarged detail sectional view through a portion of the carton top wall said view being taken on the planes of the line 6—6 in Figure 3; and

Figure 7 is a plan view of the carton blank.

Referring now particularly to the accompanying drawings in which like numerals indicate like parts throughout the several views, it will be seen that the carton of this invention differs from the conventional carton in that its top wall 8 instead of being formed by a plurality of flaps folded down one upon the other and glued together, consists of one continuous panel of the carton blank. This panel, as best seen in Figure 7, is of the same size and shape as the panel 9 which forms the bottom of the carton, and of the same length as side wall forming panels 10 and 11. The panel 11 has a glue flap 12 which is adhered to the bottom panel 9 during formation of the carton. The ends of the carton are formed by down and upturned similar flaps 13 on the top and bottom panels overlying and adhered to smaller inturned flaps 14 on the side wall panels 10 and 11. The shaded areas in Figure 7 depict the gluing areas.

While it is, of course, possible to form or set up the carton before its contents are placed therein, it is more advantageous in many instances to form the carton by wrapping the carton blank about the contents and then secure the glue joints. This is especially so in the packaging of canned beer which is, of course, done 60 on automatic or semi-automatic machines and very rapidly.

With this manner of packaging it is also possible to so proportion the carton as to have it fit the contents very snugly. In the case of canned beer the cans 15, usually a half dozen, are arranged vertically with their ends snugly engaged by the top and bottom walls of the carton and with the side and end walls of the car-

ton in close juxtaposition to and preferably gripping the adjacent sides of the cans.

To enable the carton to be conveniently handled and carried, a handle 16 is provided. This handle, when not in use, lies flat against the top wall 8 but may be quickly and easily lifted to permit inserting the hand between the handle and the top wall of the carton. In its inoperative, non-carrying or retracted position, the handle obviously does not interfere with stacking of cartons one on the other.

As best shown in Figure 2 the handle is formed of paperboard and has an elongated grip 17 connecting enlarged rectangular end portions 18. These end portions have substantial area and project laterally a considerable distance beyond the opposite side edges of the grip 17 to define abrupt shoulders 19 at the ends of the grip. Score lines 20 extend transversely across the enlarged end portions 18, parallel to the shoulders 19 to enable the extreme end portions of the enlargements to be bent down as flaps 21.

Preferably the side edges of the handle grip 17 are curved inwardly as shown to make the handle more comfortable.

To enable assembly of the handle with the carton, the top wall 8 of the carton has a pair of opposite spaced apart transverse slits 22 connected at substantially their midpoints by a long longitudinal slit 23. These slits together with longitudinally extending score lines 24 define two side-by-side elongated flaps 25 which may be displaced out of the plane of the top wall panel 8. The transverse slits 22 are preferably arcuate and convexly face each other as shown to thus produce a pair of end flaps 26 which, like the flaps 25, may be displaced out of the plane of the top panel 8.

The assembly of the handle with the carton blank is effected by an operation known in the art as "plowing" and which results in passing the handle grip 17 through the slits 22 and 23 and disposing the grip portion 17 over the longitudinal flaps 25 while leaving the enlarged end portions 18 beneath or under those portions of the top panel 8 adjacent to but outwardly of the slits 22.

The distance between the score lines 20 across the end portions of the handle is approximately the same as the full length of the top panel 8 so that when the handle is "plowed in" and lies flat against the top panel 8, the score lines 20 are substantially in line with the score lines 13' which define the end flaps 13 from the top panel 8. Hence, the flaps 21 on the ends of the handle may be folded down alongside the adjacent cans as the end flaps 13 are brought down into place.

Though as indicated hereinbefore, in the formation of the carton its walls snugly contact the adjacent surfaces of the cans there is sufficient resiliency in the carton walls and sufficient clearance between the carton walls and the cans to enable the grip portion 17 of the handle to be lifted or bowed out of flat engagement with the top 8 to allow the fingers of the hand to be inserted under the grip. Such bowing of the handle, of course, entails a slight movement of the ends of the handle toward one another, and to enable such movement the distance between the shoulders 19 at the opposite ends of the handle is slightly greater than the maximum distance between the transverse slits 22.

An important feature of the invention resides in the fact that the confinement of the down-turned flaps 21 on the ends of the handle between the end walls of the carton and the sides of the adjacent cans together with the sharpness of the bend which joins the flaps 21 to the rest of the handle arrests the movement of the handle ends toward one another before the shoulders 19 engage the ends of the transverse slits 22. If such engagement were permitted, the strain resulting from lifting force applied upon the handle would produce a shearing action upon the top wall panel at the ends of

the transverse slits. Obviously such shearing action would be objectionable.

The strain resulting from the application of lifting force on the handle is distributed over relatively large areas of the top wall panel 8 by virtue of the fact that the enlarged end portions 18 of the handle have substantial area and directly underlie the adjacent portions of the top wall panel. Thus, upon the application of lifting force on the handle the portions of the top wall panel overlying the handle enlargements 18 are pulled upwardly away from the tops of the cans therebeneath as best shown in Figure 5. This distributes the strain over a large area of the top wall panel and avoids to a large degree any concentration of lifting stress such as that which was inevitable in carrying cartons of the past as represented by the aforesaid patent to Rue.

It was found, however, that even with this improvement there is some concentration of stress in the top wall panel 8 in the regions lying generally between the ends of the transverse splits 22 and the adjacent sides and corners of the carton, with the maximum strain occurring in zones extending substantially along the lines A-B in Figure 3. The transverse splits 22, of course, greatly weaken the top wall and from experience it was found that if a tear occurred it started from the ends of these transverse slits 22 and ran out toward the side walls or the corners of the carton along the lines A-B. To guard against failure in these regions the top wall panel is reinforced by separating, and in a sense isolating, the transverse slits 22 from the areas of stress concentration by bands or lines 27-28 along which the board has been compacted to greater density.

The reinforcing bands 27 extend as chords across the ends of the arcuate slits 22 while the bands 28 continue around the ends of the slits as angularly disposed extensions of the bands 27. The specific angle of the extensions 28 is not critical as long as they lie generally crosswise to the lines A-B.

The reinforcing bands 27-28 are a species of scoring but, as shown in Figure 6, distinguish from the scoring which defines bend lines in that they are formed by indenting one face of the board with a male scoring member acting against a flat unbroken surface. This compresses and compacts the board and greatly increases its resistance to tearing, especially in a line transverse to the band or line of reinforcement.

The reinforcing bands or lines 27 also define hinge lines about which the end flaps 26 may swing in conformity with the handle as it is bowed upwardly by the application of a lifting force thereon.

From the foregoing description taken in connection with the accompanying drawings it will be readily apparent to those skilled in the art that this invention provides a handy carrying carton especially well adapted for use in packaging canned beer, that it provides a carton which is more comfortably carried and is better suited to production methods of packaging and shipping than cartons of this type heretofore available, and that it has the very important advantage of being far less subject to having the handle pull out due to failure of its anchorage.

What I claim as my invention is:

1. In a carrying carton of the character described: an apertured top wall, and a pair of opposite end wall members joined to and depending from two parallel but remote edges of the top wall; an elongated handle member having a grip portion projecting upwardly through the apertured portion of the top wall; and a pair of handle anchors joined to the ends of said grip portion internally of the carton and each comprising horizontal and vertical flanges hinged together along a line coincident with the junction between the top wall and one of said end wall members, one flange of each anchor substantially flatwise underlying and engaging the top wall adjacent to its junction with one end wall member, and the other

flange of each anchor substantially flatwise underlying and engaging the adjacent end wall member adjacent to its junction with the top wall and being disposed substantially edgewise with respect to the top wall, whereby said handle anchors are substantially nested in the corners defined by the junctions of the top and said end wall members.

2. In a carrying carton of the character described: a top wall and two upright walls joined to remote edges of the top wall, said top wall having an elongated opening therein extending lengthwise between the junctions of said top and upright walls but terminating a distance short of said junctions; and a handle for the carton formed of sheet material and having a grip portion exposed above said top wall and wider end portions of substantial area disposed inside the carton, the grip portion of the handle projecting upwardly through said elongated opening, and each of said wider end portions of the handle comprising a substantially horizontal flap portion integrally joined to the grip portion and flatwise underlying that portion of the top wall which extends beyond the adjacent end of said elongated opening, and a substantially vertical flap portion hingedly joined to the horizontal flap portion and flatwise underlying the adjacent upright wall of the carton, said angularly disposed flap portions having their hinged joints coincident with said junctions of the top and upright walls whereby said flap portions are nested in the corners defined by the junctions of the top and upright walls.

3. In a carrying carton of the character described: two remote upright walls, and a top wall joined to the upper edges of said upright walls, said top wall having an elongated slit therein extending lengthwise between the junctions of said top and upright walls and terminating in shorter slits extending crosswise of the elongated slit and near but spaced from said junctions; and a handle for the carton formed of sheet material and having a grip portion exposed above said top wall and wider end portions of substantial area disposed inside the carton, said wider end portions defining abrupt opposing shoulders at the ends of the grip portion spaced apart a distance greater than the length of said elongated slit but less than the distance between said junctions of the top and upright walls measured along said elongated slit, the grip portion of the handle projecting upwardly through said short slits and overlying the flaps defined by said elongated slit, and each of said wider end portions of the handle comprising a substantially horizontal flap portion integrally joined to the grip portion and flatwise underlying that portion of the top wall which extends beyond the adjacent end of said elongated slit, and a substantially vertical flap portion hingedly joined to the horizontal flap portion and flatwise underlying the adjacent upright wall of the carton, said angularly disposed flap portions having their hinged joints coincident with said junctions of the top and upright walls whereby said flap portions are nested in the corners defined by the junctions of the top and upright walls.

4. A package comprising a rectangular assembly of rigid containers held in tight assembled relation by an enclosing carton, said carton including a top wall and end wall members extending one from each end of said top wall and folded downwardly over the adjacent end face of the assembly, said top wall being provided with a longitudinally extending opening, the ends of said opening being spaced from the adjacent edge of the top wall, a handle member including a flat strap member having enlarged head members at each end thereof, said strap member having a width not greater than the width of said opening and coinciding therewith, said head members being positioned between said top wall and the contents of the carton at the ends of said opening and having their end portions folded downwardly over the adjacent end edge of the container assembly in substantial coincidence with the fold of the adjacent end wall member and extending downwardly between the latter and the end of the container assembly.
5. A carton blank and handle assembly formed of cardboard and adapted to be folded around a rectangular assembly of rigid containers to form a package, said blank comprising top, side wall and bottom forming sections hinged together by score lines, end closure flaps extending one from each end of said sections and hinged thereto by score lines, said top section being provided with a cut extending longitudinally thereof and terminating at each end in a transversely extending cut forming a longitudinally extending opening and providing at least one wing member normally closing said opening and a handle member including a flat strap member having an enlarged head member at each end, positioned against the inner face of said top section with said strap member positioned beneath said wing member and exposed to the outer face of said top section through said opening, said enlarged head members extending over the score lines between the top section and the adjacent end closure flaps and being provided with transverse score lines coinciding with the score lines between the top section and the adjacent end closure flaps.
